Application filed January 23, 1891. Serial No 378,846. Term of patent 3½ years.

To all whom it may concern:

Be it known that I, EMIL G. SAUER, of the city of Brooklyn, county of Kings, and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

My design consists of a body part A and a border B. Body part A consists of a large con-

tinuous scroll terminating in a smaller scroll entwined by small leaf sprays. Border part B consists of the same scroll and leaves drawn on plain ground.

What I claim as new, and desire to secure by Letters Patent, is—

1. The design for carpets, consisting of the body part A, substantially as shown.

2. The design for carpets, consisting of the border B, substantially as shown.

3. The design for carpets, consisting of the body part A and the border B, substantially as shown.
